UNITED STATES PATENT OFFICE.

RICHARD A. CUTTER, OF PEORIA, ILLINOIS.

DESIGN FOR A STOVE-DOOR.

Specification forming part of Design No. 5,807, dated April 23, 1872.

To all whom it may concern:

Be it known that I, RICHARD A. CUTTER, of the city of Peoria, in the county of Peoria and in the State of Illinois, have invented a new and Improved Design for a Combined Drop-Door and Register for Stoves or Furnaces; and do hereby declare that the following is a full, clear, and exact description thereof, reference being had to the annexed drawing making a part of this specification, in which like letters of reference refer to like parts, and in which the figure represents a front view.

This design relates to a combined drop-door and register, having a configured ornamental border around the register, and having also,

on the face side of each space intervening between the air-draughts of the register, the design or configuration as represented in Fig. 1 of the drawing.

Claim.

The design for a combined drop-door and register, as described and shown.

In testimony that I claim the foregoing design for stove-door I have hereunto set my hand this 13th day of January, A. D. 1872.

RICHARD A. CUTTER.
